Y. W. ROGERS,
COMBINATION CHAIR,
APPLICATION FILED NOV. 7, 1918.

1,310,250.

Patented July 15, 1919.

UNITED STATES PATENT OFFICE.

YUBIE WILLIAM ROGERS, OF ST. LOUIS, MISSOURI.

COMBINATION-CHAIR.

1,310,250.

Specification of Letters Patent. Patented July 15, 1919.

Application filed November 7, 1918. Serial No. 261,576.

To all whom it may concern:

Be it known that I, YUBIE WILLIAM ROGERS, a citizen of the United States, residing at St. Louis, in the State of Missouri, have invented new and useful Improvements 5 in Combination-Chairs, of which the following is a specification.

My invention relates to improvements in combination chairs in which the backs may 10 be placed in such a position as to form a desk; and the object of my improvement is to produce a chair in which, when the back is elevated on its hinges to form a table surface the same may be swung to and fro, making it convenient in sitting on and rising 15 from its seat.

I attain this object by the mechanism illustrated in the accompanying drawing, in which—

20 Figure 1 is a perspective view of the device when used as a seat at a table. Fig. 2 is a view of the device as it appears when used as an ordinary chair. Similar numerals refer to similar parts throughout the two views.

25 Numeral 1 of the drawing represents the seat of the device having a support 2 rigidly fixed near the upper corner of said seat; there is a horizontal bar 3 having one of its ends pivotally fixed by means of a pivot 4 near the upper end of support 2, a fork 5 in the free end of horizontal bar 3 co-operates 30 with a dowel at the free end of a second support 6 which is secured to a corresponding corner of seat 1 by means of a hinge 7.

There is a back 8 secured to horizontal 35 bar 3 by means of hinges 9. When back 8 is elevated on its hinges 9 to form a table surface, it is held in an elevated position by means of a swivel bar 10 which is pivoted to the central part of the upper side of horizontal bar 3.

There is a groove 11 in the upper end of support 2, into which swings the shoulder of pivot 4, to prevent the table from swinging when used as a desk; additional firmness 45 may be had by moving support 6 on its hinges 7 to engage fork 5 of horizontal bar 3.

A clamp 12 is secured to the side of back 8 to keep support 6 in an upright position when the device is used as an ordinary chair 50 as shown in Fig. 2.

Having fully described my invention, what I claim is—

A combination chair comprising a seat having a support rigidly fixed near one of 55 its upper corners, a horizontal bar having one of its ends pivotally fixed near the upper end of said support; the free end of said horizontal bar co-operating with the free end of a hinged support which is secured to an 60 opposite corresponding corner of said seat; a back having a flat surface pivotally connected with said horizontal bar, and suitable means for holding said back in a table top position, substantially as described. 65

YUBIE WILLIAM ROGERS.
